EMIL AUGUST ILEMAN, OF QUEENS, NEW YORK, ASSIGNOR TO AMERICAN SCHAEFFER & BUDENBERG CORPORATION, A CORPORATION OF NEW YORK.

REGULATING VALVE.

Application filed December 19, 1923. Serial No. 681,545.

This invention relates to temperature controlled apparatus and particularly to such apparatus for controlling a steam supply to regulate the temperature of heating means 5 for industrial purposes or of enclosures such as houses and the like.

The object of the invention is to provide a temperature controlled apparatus which will be simple and durable in construction 10 and reliable in operation.

Further objects of the invention particularly in the combination in the apparatus of mercury actuated control means will appear from the following description taken in connection with the accompanying drawings in 15 which,

Fig. 1 is an elevational view partly in section of apparatus illustrating the invention.

Fig. 2 is a vertical sectional view on line 20 2-2 of Fig. 1.

Fig. 3 is a vertical sectional view taken on the line 3-3 of Fig. 1.

Fig. 3^a is a sectional diagrammatic view showing the heat regulating means and with 25 its connection to the control means indicated by broken lines.

Fig. 4 is a sectional view of the control bulb which is connected to the apparatus of Figs. 1, 2 and 3 in any desired manner.

Fig. 5 is a sectional view similar to Fig. 3 and illustrating a modified form of valve 30 means, and

Fig. 6 is a vertical sectional view of a detail of Fig. 1.

In the specific embodiment of the invention shown in the drawings a compressed air supply line 5 is connected to a feed line 6 through a valve 7 which valve is to be controlled by temperature variations at any 35 desired remote point, and the air supply to the pipe 6 in turn will control a valve or other means to regulate the supply of heat.

The valve 7 has a seat 8 with which cooperates the ball 24 which is pressed against 45 said seat by spring 25, spring 25 exerting a downward force in excess of the upward pressure of the compressed air on the under surface of the ball. The valve 7 is opened to a variable extent by lifting the ball 24 50 from its seat 8 to a variable distance. This is accomplished by movement of the stem 10 having the tapered end 9 engaging under the ball 24 to lift it against the pressure of the spring 25.

Mercury actuated means are provided to

move the stem 10. At its lower end the stem 10 is pivoted at 11 to the yoke member 12 each end of which at 13 is pivoted to the outer ends of the spiral tubes 14 connected by the off-sets 15 to the tube 16 which in turn is connected by tube 17 to the control bulb 18 placed at any desired point where the temperature is to be regulated.

The bulb 18, connecting tube 17, U-tube 16 and spiral tubes 15, 14 are filled with 60 mercury. A rise in temperature at the bulb 18 will cause the mercury therein to expand and this expansion will be transmitted through the continuous mercury column to the spiral tubes 14 causing these spirals to 65 tend to straighten or unwind so as to lift upward on the ends of the yoke 12 and thus press upward on the stem 10 with a variable pressure dependent upon the temperature at the bulb 18. The passages through the tubes 70 17, 16, 15 and 14 are very small in cross section so that the volume of mercury in these tubes is very small and the changes in volume of the mercury column in these tubes, due to temperature variation is so small as to 75 be negligible. By making the passages through these tubes only sufficient to transmit the pressure from bulb 18 to the spirals 14, the full effect of the changes in volume of the mercury in bulb 18 is accurately transmitted to the stem 10 and valve 7 without appreciable variation due to temperature conditions in the pressure transmitting mercury 80 column.

The valve seat 8 is carried by a bushing 20 90 inserted in a slidable sleeve 21 adjustable by means of the rotatable head 22 screw threaded into the stationary block 23. This permits the position of the valve 24 to be varied with relation to the stem 10 so that 95 the opening action of the stem may be set for any predetermined temperature at the bulb 18. The strength of the spring 25 while sufficient to overcome the compressed air pressure on the lower surface of the ball 24 100 is not sufficient to overcome the upward pressure exerted by the stem 10 when the spirals 14 are expanded by pressure from the bulb 18. The movement of the stem 10 raises and lowers the ball 24 while the spring 25 maintains a yielding pressure downward on the end of the stem until the ball 24 is set against the end of the bushing 20.

The spiral tubes 14 are contained in a closed chamber 27 in the casing 28, the U- 110

tube 16 at each of its branches being sealed through the detachable floor portion 29 of said casing. The compressed air supply from pipe 5 maintains a substantially constant pressure of about fifteen pounds, for instance in the enclosure 27. Gauges may be connected to the upright pipes 5', 6' to measure the air pressure on each side of the valve 7.

10 When the valve 7 is opened by the stem 10 air under pressure in chamber 27 will pass through the valve and into the pipe 6 to control the heat supply in any desired manner. For instance, as indicated in Fig. 15 3^a, the pipe 6 may supply air pressure to the chamber 32 above the diaphragm 33 carrying the valve 35 normally held upward in open position by the spring 34. Air passage 6 is vented to the atmosphere by 20 means of leak 30 (see Figs. 1 and 6). The size of the leak or vent is adjustable by means of adjusting screw 36, co-operating with a seat 37. By means of leak 30 and a varying opening of valve 7 it is possible to 25 maintain a varying pressure in chamber 32. When the valve 7 opens, air pressure through pipe 6 and in chamber 32 depresses the valve 35 toward closed position a variable amount depending upon the extent of the opening 30 of valve 7, and thus throttles the steam supply through valve 35 to lower the temperature at the bulb 18. Conversely a closing movement of the valve 7 will allow leak opening 30 to reduce the pressure in chamber 32 to permit the spring 34 to open the valve 35 and increase the supply of steam so as to raise the temperature at the bulb 18.

Instead of the spring pressed ball valve construction shown in Figs. 1 and 3, the 10 stem 10, as shown in Fig. 5, may be formed with a tapered end 38 cooperating with a seat 39 in the adjustable sleeve 21' to variably throttle the air pressure according to the movement of the stem 10. Such a valve 15 arrangement will require a corresponding change in the regulating valve means because an upward movement of the stem 10 caused by an increase in temperature at the bulb 18, will decrease, not increase, the 20 supply of air to the steam valve actuating means. With the valve construction of Fig. 5, therefore, the diaphragm 33 and valve 35 of Fig. 3^a will be so arranged that a decrease in pressure on the diaphragm will close the 25 valve 35 instead of opening it as in Fig. 3^a.

By enclosing the spirals 14 and the stem 10 in the pressure supply chamber 27 there are no close or packed fittings between movable parts and the valve control freely floats 30 with the guide ribs 31 of the stem 10 lightly sliding within the bushing 20 so that the stem movement may be made extremely sensitive to relatively small pressure variations, while at the same time the very small volume 35 of mercury required for the spiral tubes 14

reduces the error due to temperature variations to a minimum. The spirals 14 will thus give an accurately controlled upward pressure to precisely and reliably operate the valve 7. The continuous column of mercury in the bulb 18 and the connecting tube 17 and the U-tube 16 and the spirals 14, 15 completely fills the space within these parts without interruption by intermediate air spaces or the like. The apparatus of this 70 invention combines sensitiveness with accuracy and adaptability; the range of the temperature control may be made long or short by changing the size of the bulb 18. A short range may be used with the beginning 75 of that range at any temperature between 0° F. for instance, and nearly 1000° F. This is accomplished by using a size of bulb 18 holding a sufficient quantity of mercury to provide the necessary expansion for 80 the prescribed range and by providing the mercury filled system with a certain initial pressure under which the expansion of the mercury will begin to expand the spring 85 at a low point of the range. Mercury is a liquid throughout a wide range of temperatures and in the system of this invention will remain unaffected for an indefinite period and permanently operative to convert 90 the temperature changes at the bulb 18 into 95 movements of the control valve member 9, 10.

I claim:—

1. In a temperature controlled system the combination with a valve adapted to regulate a supply, of means for actuating the same comprising an extensible member of comparatively small capacity adapted to be moved by internal fluid pressure, said extensible member being adapted to have mechanical connection with said valve for effecting actuation thereof, a bulb member of comparatively large capacity subjected to temperature variations, a connecting tube between said members, and mercury forming a continuous liquid column connection between said bulb and said extensible member. 100

2. In a temperature controlled system the combination with a valve adapted to regulate a supply, of means for actuating the same comprising an extensible member of comparatively small capacity adapted to be moved by internal fluid pressure, said extensible member being adapted to have mechanical connection with said valve for effecting actuation thereof, a bulb member of 110

comparatively large capacity subjected to temperature variations, a connecting tube between said members, and mercury forming a continuous liquid column connection between said bulb and said extensible member, said mercury filling said extensible member. 115

3. In a temperature controlled system the combination with a valve adapted to regulate a supply, of means for actuating the same comprising a spiral tube member of com- 120

- paratively small capacity adapted to be
moyed by internal fluid pressure, said spiral
tube member being adapted to have mechan-
ical connection with said valve for effecting
5 actuation thereof, a bulb member of com-
paratively large capacity subjected to tem-
perature variations, a connecting tube be-
tween said members, and mercury forming
a continuous liquid column connection be-
10 tween said bulb and said spiral tube member.
4. In a temperature controlled system the
combination with a valve adapted to regu-
late a supply, of means for actuating the
same comprising a source of fluid under
15 pressure, a control valve therefor, an exten-
sible member adapted to have mechanical
connection with said valve to move it by in-
ternal fluid pressure, a bulb member sub-
jected to temperature variations, a connect-
20 ing tube between said members, and mercury
forming a continuous liquid column connec-
tion throughout said bulb and said exten-
sible member.
5. In a temperature controlled system the
25 combination with a valve adapted to regu-
late a supply, of means for actuating said
valve comprising a chamber supplied with
fluid under pressure, a control valve for said
fluid, an extensible member in said chamber
30 adapted to move said valve by internal fluid
pressure, a bulb member subjected to tem-
perature variations, a connecting tube be-
tween said members, and mercury forming
a continuous liquid column connection
35 throughout said bulb and said extensible
member.
6. In a temperature controlled system the
40 combination with a valve adapted to regu-
late a supply, of means for actuating the
same comprising an extensible member
adapted to be moved by internal fluid pres-
sure, said extensible member being adapted
45 to have mechanical connection with said
valve for effecting actuation thereof, a bulb
member subjected to temperature variations,
a connecting tube between said members, and
mercury forming a continuous liquid column
50 connection throughout said bulb and said
extensible member, said mercury filling said
extensible member and being under a pre-
determined pressure with which said mer-
cury will begin to actuate said extensible
55 member at a predetermined bulb tempera-
ture.
7. In a temperature controlled system the
combination with a valve adapted to regu-
late a supply, of means for actuating said
valve comprising a pair of spiral tube mem-
bers of comparatively small capacity
60 adapted to be moved by internal fluid pres-
sure and a yoke member connecting said tube
members, a bulb member of comparatively
large capacity subjected to temperature va-
riations, a connecting tube between said
65 members and mercury forming a continuous
liquid column connection throughout said
bulb and tube and spiral tube members.
8. A controlling mechanism for tempera-
ture, pressure or the like, comprising a plu-
rality of expansible spiral sensitive elements,
70 a movable member, and means connecting
said expansible sensitive elements to each
other and to said movable member so as to
give to said member a rectilinear movement
due to the movement of each of said spiral
75 elements.
9. A mechanism for controlling tempera-
ture, pressure or the like, comprising a mov-
able controlling member, a plurality of ex-
pansible sensitive elements normally opera-
80 tive to expand simultaneously, and means
for effecting movement of said member by
said elements even when said elements have
substantially the same degree of expansion
85 and for distributing the actuating forces
therefrom substantially equal over all of
said elements.
10. A mechanism for controlling tempera-
ture, pressure or the like, comprising a mov-
able controlling member, a pair of spiral ex-
pansible sensitive elements having free ends,
90 and means for actuating said movable mem-
ber having operative connection with the
free ends of each of said spirals.
11. A mechanism for controlling tempera-
ture, pressure or the like comprising a line-
arly movable valve, and means for actuating
the same including a pair of expansible sen-
sitive elements adapted to have relative
100 movement therebetween and normally oper-
ative for simultaneous, substantially uni-
form expansion, and means connecting said
elements and having provision for engaging
said valve to move the same.
12. A mechanism for controlling tempera-
ture, pressure or the like, comprising a line-
arly movable valve, and means for actuating
the same comprising a plurality of spiral ex-
pansible sensitive elements, and substantially
110 linearly movable means for engaging said
valve having operative connection with said
spiral elements whereby any expansion
thereof will maintain linear movement of
said valve engaging member.

EMIL AUGUST ILEMAN.
